UNITED STATES PATENT OFFICE

165,852

COMBINED ASH TRAY AND WRITING INSTRUMENT

Earl Lewis, Philadelphia, Pa.

Application April 5, 1950, Serial No. 8,990

Term of patent 3½ years

(Cl. D74—1)

To all whom it may concern:

Be it known that I, Earl Lewis, a citizen of the United States, residing at Philadelphia, Pennsylvania, have invented a new, original, and ornamental Design for a Combined Ash Tray and Writing Instrument, of which the following is a specification, reference being had to the accompanying drawing, forming part thereof:

Fig. 1 is a perspective view of a combined ash tray and writing instrument, showing my new design.

Fig. 2 is a top plan view of the same.

Fig. 3 is a bottom plan view of the same.

Fig. 4 is an exploded side elevational view of the same.

I claim:

The ornamental design for a combined ash tray and writing instrument, as shown.

EARL LEWIS.
